UNITED STATES PATENT OFFICE.

CHARLES F. HOWE, OF GREENLEAF, KANSAS.

PLATEN PRINTING-MACHINE.

SPECIFICATION forming part of Letters Patent No. 376,956, dated January 24, 1888.

Application filed May 2, 1887. Serial No. 236,861. (No model.)

To all whom it may concern:

Be it known that I, CHARLES F. HOWE, of Greenleaf, in the county of Washington and State of Kansas, have invented a new and Improved Platen Printing-Machine, of which the following is a full, clear, and exact description.

The object of my invention is to provide a new and improved printing-press which is simple and durable in construction, very effective in operation, and specially adapted for doing general newspaper printing.

The invention consists in the construction and arrangement of various parts and details and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a side elevation of my improvement. Fig. 2 is a sectional plan view of the same with parts of the feed-table broken out and the platen removed. Fig. 3 is a vertical cross-section of the same on the line *x* *x* of Fig. 1. Fig. 4 is an enlarged sectional elevation of the extension ink-roller arm. Fig. 5 is an enlarged side elevation, partly in section, of the platen-pitman and its connection with the platen. Fig. 6 is an elevation of the same at right angles to Fig. 5. Fig. 7 is an enlarged plan view of the gripping-fingers and tripper. Fig. 8 is a side elevation of the same. Fig. 9 is an end elevation of the same; and Fig. 10 is a similar view of the gripping-fingers and tripper, showing the gripping-fingers open.

The main frame *A*, of suitable construction, is provided near its middle with the upwardly-extending standards *A'* and *A''*, of which the standard *A'* is provided with a bracket, *A'*, extending upward and carrying, in conjunction with said standard *A'*, the driving-shaft *B*, provided with suitable means for rotating the same either by hand, foot, or steam power. To the main driving-shaft *B* is secured the gear-wheel *B'*, meshing into the gear-wheel *B''*, secured on one outer end of the platen-shaft *C*, mounted in suitable bearings in the standards *A'* and *A''*. On the other end of the platen-shaft *C* is secured the gear-wheel *C'*,

which meshes into the gear-wheel *C''*, secured to a short shaft, *C'*, having its bearings in the standard *A''* and in a bracket, *A'*, extending outward from said standard. The shaft *C'* carries a fly-wheel, *C''*, for maintaining the momentum of the platen-shaft *C*. On the shaft *C*, between the standards *A'* and *A''*, are formed the crank-arms *C'*, connected by the platen-pitmen *D* with the platen *E*. The pitmen *D* can be lengthened or shortened to suit the impression which it is desired to make, and each pitman consists of two parts, *D'* and *D''*, connected at their screw-threaded ends by the nut *D''*, which, when turned, lengthens or shortens the pitman.

In the part *D''* of each pitman *D* is secured the pin *B'*, held in the vertical slots *E'*, formed in the standards *E'*, secured to the top of the platen *E*. The lower end of the part *D''* of the pitman *D* rests against the spring *E''*, connected to the latter and held between the standards *E'*, and resting with its ends on the top of the platen *E*: This arrangement permits of giving a dwell on impression, as the platen becomes yielding in connection with the pitmen and the springs *E''*. The platen *E* is guided in its up-and-down motion by the rods *F*, secured to the corners of the platen, extending upward and passing through fixed arms *F'*, secured to the standards *A'* and *A''*. Springs *F''* are held between said arms *F'* and the platen *E*, so as to support the platen *E*, thus relieving the platen-shaft *C* from strain. The platen *E* is held above the type-table *G*, supported by suitable means from the main frame *A*, and extending horizontally from near one side to the other of said frame. The type-table *G* supports, in the usual manner, the chase *G'*, carrying the type from which the impression is to be made.

The upper ends of the type are in line with the upper edges of the main frame *A*, and on the latter travel the inking-rollers *H*, connected at their outer ends with the arms *H'*, to each of which is pivoted in the middle the extension ink-roller arm *J*, consisting, principally, of two parts, *J'* and *J''*, telescoping one in the other, and of which the part *J'* is provided on its lower end with a collar, *J''*, against which rests one end of a spring, *J''*, coiled on said part *J'*, inclosed in the hollow part *J''*, and resting with its upper end against the

- closed end of said hollow part J^2 . The pivot J^3 of the extension ink-roller arms J is at the lower end of the hollow parts J^2 , and is supported by brackets A^5 , secured to the main frame A . On the part J^2 is formed a pin, J^6 , on which is pivoted a link, K , pivotally connected with the arm K' , secured to the transverse shaft K^2 , mounted in brackets A^6 , formed on the main frame A .
- 10 On one end of the shaft K^2 is secured the crank-arm K^3 , connected by the link K^4 with the crank-arm L' , formed on the shaft L , mounted in suitable bearings on the main frame A and the bracket A^7 . On the shaft L is secured the bevel gear-wheel L^2 , meshing into the bevel gear-wheel L^3 , secured to the vertical shaft L' , mounted in the brackets A^3 and A^7 , and carrying at its upper end the bevel gear-wheel L^5 , meshing into the bevel gear-wheel L^6 , secured to the main driving-shaft B .
- 15 On the outer ends of the main frame A are secured the brackets A^8 , made of spring-steel or other suitable elastic material. On the brackets A^8 , at each end of the frame A , are mounted the shafts N and N' , respectively, each carrying pulleys N^2 , placed suitable distances apart. Over each corresponding set of pulleys N^2 on the shafts N and N' passes an endless belt, O , adapted to carry the paper to
- 20 be printed from the feed-table S to the other end of the frame A , and delivering the paper to the usual fly connected with the machine. Each of the endless belts O is provided at one, two, or more places, which are equal distances apart, with gripping-fingers P , each consisting of a fixed arm, P' , on which is pivoted a spring-arm, P^2 , said arms P' and P^2 extending to one side of the belt O , and being connected by a spring, P^3 , which holds the gripping-fingers
- 25 in a closed position.
- 30 The gripping-fingers are adapted to be opened by the trippers Q , secured to the main frame A on each side, directly under the feed-table S . Each tripper Q is provided with an inclined top adapted to engage the outer ends of the gripping-fingers P , so that when said outer ends enter the tripper Q then the fingers are opened when passing toward the small end of said tripper Q , as illustrated in Fig. 10.
- 35 The feed-table S is supported from the main frame at the rear end and is held in the usual inclined position, as shown in Fig. 1. The shaft N , which operates the belts O , is rotated by an endless belt, N^4 , passing over the pulley N^5 , secured to the rear shaft, N , and also passing over a pulley, N^6 , secured to the shaft L , which receives its rotary motion from the main driving-shaft B by the gear-wheels L^6 , L^5 , L^3 , and L^2 , connected as above described.
- 40 The operation is as follows: When the main shaft B is rotated, then its gear-wheel B' , meshing into the gear-wheel B^2 , rotates the platen-shaft C , which, by its crank-arms C' and the pitmen D , imparts an up-and-down motion to
- 45 the platen E . The paper to be printed is fed from the feed-table S upon the belts O , which travel in the direction of the arrow a' , and the

lower end of the paper is passed between the fingers of the grippers P , which are then in an open position, as shown in Fig. 10, as they then pass through the narrow ends of the trippers Q , and as soon as the paper is thrown on the gripping-fingers then the latter leave the trippers Q , whereby the spring P^3 closes the gripping-arms, thus holding the front end securely in place and carrying the paper forward on the belts O in the direction of the arrow a' . As soon as the grippers P arrive at the outer end of the platen E the fingers strike against the lugs E^4 , projecting downward from the platen E , whereby the forward motion of the belts O is interrupted, and the belt N^4 , imparting motion to said endless belts O , is allowed to slip over its pulley N^3 on the shaft N . The platen E has then already commenced to move downward by the action of the crank-arms C' and the pitmen D , and by the continued motion of which the paper and the belts O are moved downward with said platen upon the chase G' , and the paper receives an impression from the type in said chase G' . The brackets A^8 , supporting the shafts N and N' , being of elastic material, are drawn inward toward each other on the downward motion of the platen E , pressed on the upper parts of the belts O , and when the platen again rises then the elastic nature of the brackets A^8 forces them to assume their normal position, as shown in Fig. 1. As soon as the impression is made, then the platen E rises again and permits the belts O to assume their normal position by the outward motion of the brackets A^8 , as above described. The platen rises sufficiently so that its lugs E^4 disengage the gripping-fingers P , whereby the belts O are again permitted to travel forward in the direction of the arrow a' , as the pulley N^3 is again free to rotate by the action of the belt N^4 . The paper is carried to the outer ends of the belts O and delivered to the fly in the usual manner. When the platen E commences to rise, then the inking-rollers H travel from the inking-rollers R toward the front, thus passing over the type in the chase G' and inking the same, after which the rollers H travel backward again to their rear position near the rollers R until the platen E has descended and made the impression. This forward and backward motion of the inking-rollers H is accomplished by the swinging motion imparted to the extension ink-roller arms J by the links K , connecting said extension ink-roller arms J with the arm K' , secured to the shaft K^2 , receiving an oscillating motion from the rotating shaft L , connected by the crank-arm L' and the link K^4 with the crank-arm K^3 on said shaft K^2 . The relative arrangement between the crank-arms C' on the platen-shaft C and the crank-arm L' on the shaft L is such that the platen E is carried downward to make its impression while the inking-rollers H are at their rear position, as above described. When the platen E rests on the type in the chase G' , then the crank-arms C' have not yet obtained their

lowest position, and the pitmen D are now moved downward against the springs E³, so that a yielding or soft impression is given to the paper by the platen E. The pressure with which the platen presses the paper upon the type is regulated by adjusting the nuts D³ so as to lengthen or shorten the pitmen D, thereby causing the springs E³ to press with more or less force against the platen and said pitmen D, thus causing a dwell of platen E on the type. When the ink-rollers H travel forward and backward on the main frame A, the rod J' of the extension roller-arm J is drawn in and out of the hollow part J² by the action of the swinging motion of said part J² and the spring J⁴, which is compressed when said part J² assumes an inclined position.

Having thus fully described my invention, I claim as new and desire to secure by Letters Patent—

1. In a printing-press, the combination, with a platen, of endless belts carrying the paper and held below said platen, pulleys over which said endless belts pass, and elastic brackets supporting said pulleys and disposed to project obliquely outward from the main frame, whereby said brackets yield bodily inwardly when the platen presses the upper parts of the endless belts downward, substantially as shown and described.

2. In a printing-press, a platen having an up-and-down motion, a type-table carrying the type and held below said platen, and inking-rollers adapted to travel over the type on the type-table between said platen and the type-table, in combination with endless belts carrying the paper and held at their upper parts between said platen and said type-table, pulleys over which said belts pass, and elastic brackets supporting said pulleys, so that when the platen presses the upper parts of said endless belts downward the elastic brackets yield, and means, substantially as described, for imparting an up-and-down motion to said platen, a rotary motion to said pulleys, and a forward and backward motion to said inking-rollers, substantially as shown and described.

3. In a printing-press, the combination, with the platen having an up-and-down movement and provided with a pendent lug, of the belts provided with grippers held in their closed position by springs, and trippers, which lug is adapted to have contact with said grippers, while the grippers are adapted to be opened by the trippers, substantially as set forth.

4. In a printing-press, the combination, with the platen E, of the pitmen D, adapted to be lengthened and shortened and pivotally connected with said platen, and the springs E³, held between the lower ends of said pitmen and said platen, substantially as shown and described.

5. In a printing-press, the combination, with the platen E, provided with the slotted standards E', of the pitmen D, adapted to be lengthened and shortened and pivotally connected with said slotted standards, and the springs E³, resting on the platen between said standards and pressing against the lower ends of said pitmen, substantially as shown and described.

6. In a printing-press, the combination, with the platen E, receiving an up-and-down motion and provided with a lug, E⁴, of the belts O, held with their upper parts below said platen E, and the grippers P, adapted to carry the paper under the platen and strike against said lug E⁴, so as to interrupt the forward motion of said belts O, substantially as shown and described.

7. In a printing-press, the combination, with the main shaft B, of the transverse shaft C, connected with said main shaft B and adapted to operate the platen, the crank-shaft L, operated from said main shaft B and adapted to impart a rotary motion to the endless belts O, and the oscillating shaft K², operated from said crank-shaft L and adapted to impart a forward and backward motion to the inking-rollers H through the arm K', secured to the transverse shaft K², and the link K, pivotally connected to the said arm and to the ink-roller-carrying arm J, substantially as shown and described.

8. In a printing-press, the combination, with the main shaft B, of the transverse shaft C, connected with said main shaft B and adapted to operate the platen, the crank-shaft L, operated from said main shaft B and adapted to impart a rotary motion to the endless belts O, and the oscillating shaft K², operated from said crank-shaft L and adapted to impart a forward and backward movement to the inking-rollers H by means of the extensible arm J, having connection with the ink-roller and with the crank-shaft L, substantially as set forth.

CHARLES F. HOWE.
